UNITED STATES PATENT OFFICE.

ENOS L. WALKER, OF ST. LOUIS, MISSOURI.

WOOD FABRIC.

1,265,841.

Specification of Letters Patent. Patented May 14, 1918.

Application filed August 27, 1917. Serial No. 188,381.

To all whom it may concern:

Be it known that I, ENOS L. WALKER, a citizen of the United States, residing at city of St. Louis, State of Missouri, have invented a certain new and useful Improvement in Wood Fabric, of which the following is a full, clear, and exact description, such as will enable others skilled in the art to which it appertains to make and use the same, reference being had to the accompanying drawings, forming part of this specification.

My invention relates to a new article of manufacture which may be properly termed a wood fabric inasmuch as it is made up of a mat which is woven from comparatively thin strips or splints of wood, said mat being interposed between two or more layers of wood veneer. The principal object of my invention is to provide a comparatively simple and inexpensive wood fabric which, by reason of the disposition of the material entering into its construction, will not split, warp, shrink or expand. By virtue of the fact that my improved wood fabric is comparatively light and at the same time very strong and durable, it is particularly adapted for a wide variety of uses, for instance, in the manufacture of all forms of boxes, containers, packing and shipping cases, baskets, and the like, and further, as sheathing or lining for buildings, cars and the like.

With the foregoing and other objects in view, my invention consists in certain novel features of construction hereinafter more fully described, claimed, and illustrated in the accompanying drawing, in which,

Figure 1 is a perspective view of a section of the wood fabric contemplated by my invention, portions thereof being broken away in order to more clearly illustrate the arrangement of the members comprising said fabric.

Fig. 2 is an enlarged cross sectional view taken approximately on the line 2—2 of Fig. 1.

Fig. 3 is an enlarged cross sectional view taken approximately on line 3—3 of Fig. 1.

As illustrated in the accompanying drawing, the central portion of the wood fabric of my improved construction is made up of a mat, the same being composed of comparatively thin wooden strips or splints 10, the same being formed so that the grain of the wood runs lengthwise and these strips or splints are preferably woven so that one

series lies substantially at right angles to the other series. The edges of the strips or splints of one series may lie immediately adjacent to each other, as illustrated in Fig. 2, or said edges may be spaced a slight distance apart, as illustrated in Fig. 3; and further, one series of strips or splints may be arranged with their edges immediately adjacent to each other, while the strips or splints of the opposite series may be spaced a slight distance apart, which latter arrangement is illustrated in Fig. 1. Both faces of the mat thus constructed are coated with a suitable adhesive, such as glue, after which comparatively thin sheets of wood veneer 11 are applied to the glued faces and after the glue has become thoroughly dry and set, the wood fabric is ready for use.

In the manufacture of my improved fabric the glue may be applied to the mat in any suitable manner, either with a brush or by passing the fabric between rollers which are supplied with glue or an adhesive from a suitable receptacle. To facilitate the drying and hardening of the adhesive, the finished sheets of material may be placed in a suitable drying room, and, if desired, a number of the sheets may be laid one on top of another while drying with a suitable weight on top of the pile to maintain the individual sheets in flat condition. If desired, the strips 10 forming the mat may be treated with a sizing or suitable wood filler before being woven into mat form or before the glue or adhesive is applied. Sufficient glue or adhesive is used to practically fill the spaces and interstices between the adjacent edges of the strips 10 and also to fill the small triangular spaces which are formed between the edges of one series of strips and the adjacent faces of the oppositely disposed strips. In applying the sheets 11 to the mat, it is desirable, although not necessary, that said sheets may be arranged so that the grain of the wood in one sheet runs substantially at right angles to the direction of the grain of the wood in the opposite sheet. In some instances, it may be found desirable to dispense with the facing sheets of wood veneer and use in place thereof sheets of comparatively heavy and tough paper; or, if desired, a sheet of wood veneer may be used as one facing sheet and a section of paper as the other facing sheet.

Wood fabric of my improved construc-

tion can be very easily and cheaply manufactured, is comparatively light, strong, substantial and durable and therefore can be advantageously used for the manufacture of boxes and containers, particularly those utilized for shipping and storage purposes, and said fabric can likewise be efficiently and economically used for sheathing and panels in the construction of buildings. By virtue of the disposition of the strips and sheets of material of which my improved fabric is formed, said fabric will not split, and likewise will not warp, shrink, or expand, even under abnormal variations of temperature.

15 I claim:

1. As a new article of manufacture, a wood fabric composed of a mat woven from comparatively thin wooden strips, and a facing sheet of comparatively thin material applied to one of the faces of said mat.
2. As a new article of manufacture, a wood fabric composed of a mat woven from comparatively thin wooden strips, and facing sheets of comparatively thin material applied to both faces of said mat.
3. As a new article of manufacture, a wooden fabric composed of a mat woven from comparatively thin wooden strips, the same being arranged so that the grain of the wood in the strips of one series runs at right angles to the grain of the wood in the strips of the other series, and facing sheets of com-

paratively thin material secured to the faces of said mat.

4. As a new article of manufacture, a wooden fabric composed of a mat woven from comparatively thin wooden strips, the same being arranged so that the grain of the wood in the strips of one series runs at right angles to the grain of the wood in the strips of the other series, and facing sheets of wood veneer secured to the faces of said mat, said sheets of wood veneer being arranged so that the grain of the wood of one sheet is disposed substantially at right angles to the grain of the wood of the other sheet.

5. As a new article of manufacture, a wood fabric composed of a mat woven from comparatively thin strips of wood, a sheet of comparatively thin material applied to one of the faces of said mat, and a sheet of wood veneer applied to the other face of said mat.

6. As a new article of manufacture, a wood fabric comprising a mat woven from comparatively thin strips of wood, and facing sheets of wood veneer applied to both faces of said mat and permanently secured thereto by a suitable adhesive.

In testimony whereof I hereunto affix my signature this 25th day of August, 1917.

ENOS L. WALKER.
